OIL FILTER FOR INTERNAL COMBUSTION ENGINES

Frank H. Griffith, Indiana, Pa.

Application January 21, 1941, Serial No. 375,347

1 Claim. (Cl. 210—183)

The present invention consists of an oil filter for internal combustion engines and is especially adapted for use on heavy duty engines in farm tractors, road making machinery, etc. With engines of this character it is frequently necessary to change the oil daily due to the constant prevalence of dust while the engine is in operation.

My invention contemplates a filter the capacity of which is greatly in excess of conventional filters and equipped with multiple filtering means of a kind and arrangement to positively delete contaminating agents, such as dirt, wax, moisture, acid, etc., from the oil, permitting use of the latter for an indefinite period of time.

It is a further object of this invention to provide a filter of inexpensive construction which may be easily and quickly disassembled, for repacking or renewing, even by a person unskilled in the art, this having been demonstrated in actual instances where the device of the present invention is in use. In a typical case, an automobile engine equipped with my filter has been operated in the car for more than 82,000 miles, the filter being repacked only three times at a cost of five cents per repack. In this cited instance there has been no manifestation of loss of engine efficiency and the engine has, during this period, undergone no repairs.

Other objects of the invention will be apparent from the following description of the present preferred form of the invention taken in connection with the accompanying drawing wherein:

Fig. 1 is a vertical sectional view of a filter constructed in accordance with the present invention.

Fig. 2 is a cross sectional view taken on the line 2—2 of Fig. 1 looking in the direction of the arrows, and

Fig. 3 is a detailed fragmentary sectional view of the inner shell showing to advantage the burrs issuing from the walls of the perforations.

The device of my invention includes a casing 4 which may be of cylindrical contour and provided with a dished base having an opening therein adapted for the reception of a nipple 5, the lower reduced end of which latter extends through the opening in the base of the casing and is welded or otherwise fixedly secured to the latter. The upper end of the casing is open and has the terminal thereof bent outwardly at right angles to provide a flange 6 the flange being adapted to have superimposed thereon a washer 7. The open end of the casing is adapted to be closed by a cover 8 which is preferably symmetrical with the base of the casing 4 and is

equipped with a flange 9 the outer margin of which is bent at right angles to provide a lip or annulus 10 which circumscribes the washer 8 and flange 6. The cover 8 is provided on its inner wall with a ring or band 11, a part of which bends below the flange 7 so as to bridge the gap between the superposed flanges 6 and 7 for an obvious purpose.

Mounted within the casing 4 are a pair of perforate members the outer of which is indicated at 12 and the inner at 13. These members constitute outer and inner shells respectively each of which has perforations 14 therein through which the oil is adapted to flow in passing from the casing inlet opening 15 to the outlet bore 16 of the nipple 5.

The outer shell 12 may be of cylindrical contour and includes a friction tight bottom closure 17 which engages annular flange 18 the latter being formed by bending the bottom of the shell inwardly in spaced relation to the inner periphery of the shell. The top of the shell body 12 is bent inwardly to provide a lip 19 of arcuate configuration which is adapted for slidable engagement with a perforate closure 20 the latter forming the top of the outer shell 12. Centrally the closure 20 is pressed upwardly to provide a boss 21 which overhangs the upper curled end 22 of the inner shell 13. Interposed between the boss 21 and said curled end 22 is a washer 23. By this arrangement possibility of concaving the closure 20 is reduced to a minimum. The lower end of the inner shell extends through and is engaged with the lower face of the bottom closure 17 in overhanging relation to the nipple 5. A washer 24 is interposed between the lower end of the inner shell and the top of said nipple as illustrated to advantage in Fig. 5. The shells 12 and 13 are anchored in the casing 4 by suitable means which in the present invention must consist of a tube 25 one end of which is detachably engaged with the nipple 5, the opposite end being engaged through a complementary opening formed in the boss of the closure 20 and secured by a nut 26. The upper end of the tube 25 is provided with internal threads which engage corresponding threads formed on the shank of a nut 27.

The outer shell is adapted for the reception of a bulk filtering material 28, such as cotton waste, which completely surrounds and encases the inner shell 13. The inner shell is wrapped with a sheet of filtering material 29 of considerably higher density than the waste 28, consisting of wool felt or a like material.

The perforations 14 of the inner shell 13 have

burrs 18 issuing outwardly from the walls thereof the burrs being engaged with the sheet 29 of filtering material. Not only do the burrs tend to retain the sheet from displacement but by this structure porous shells are provided over the perforations 14 at a point spaced outwardly from the latter as shown to advantage in Fig. 2.

In using the device of the present invention the oil from the engine pump enters the casing opening 15 and passes through the perforations in the wall and top of the outer shell 12. All the heavy extraneous agents are intercepted by the filtering material 29 before contact of the oil is made with the filtering sheet 29. The latter, by reason of its construction and also by reason of its arrangement on the burrs of the inner shell 13, completes the interception of all extraneous materials which may have passed through the primary filter 28. It is apparent therefore that all materials eluding interception in the bulky mass 28, which constitutes the primary filter, are removed from the oil preparatory to complete passage of the latter through the secondary filter 29. After having passed through said secondary filter and the perforations 14 of the shell 13, the oil is permitted to gravitate downwardly in said shell and through an outlet perforation 30 formed in the tube 25, the perfora-

tions communicating with the bore 16 of the nipple 5.

By reason of the construction and arrangement of the inner shell and its appurtenances, a larger filter area is provided in the casing 12 in order to effect a more thorough filter action.

It is apparent that various changes may be made in this invention within the scope of the claim hereto appended.

10. What is claimed is:

A filter for internal combustion engines including a casing with oil inlet and outlet openings, a perforate outer shell mounted in the casing and equipped with a concentric perforate inner shell, 15 bulk filtering material mounted in said outer shell, a sheet filtering element, of greater density than the material in said outer shell, wrapped around the inner shell, the bulk completely enveloping and engaging said sheet filtering element, burrs extending from the walls of said perforations for engagement with the sheet filtering material, a tube mounted within the inner shell having an inlet opening in communication with the oil outlet opening of the casing, and 20 independent means engaged with each end of the tube and said shells for connecting the tube and shells to the casing.

FRANK H. GRIFFITH.
